UNITED STATES PATENT OFFICE

2,506,610

VENEER-CLIPPER SAFETY GUARD

Lincoln A. Mueller, Missoula, Mont.; dedicated to the free use of the People in the territory of the United States

Application July 11, 1946, Serial No. 682,759

2 Claims. (Cl. 164—47)

(Granted under the act of March 3, 1883, as amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to me of any royalty thereon.

I hereby dedicate the invention herein described to the free use of the People in the territory of the United States to take effect on the granting of a patent to me.

This invention relates to a safety guard used with a machine for clipping the edges of a sheet of veneer, such as a wood ply of the type used in laminated wood assemblies, and has among its objects the provision of a guard which is positioned on the machine forward of the knife and low enough to prevent the operator from running his fingers under the guard into the path of the knife, yet not to interfere with visibility of the knife especially where it comes in contact with the ply, and to provide a guide for guiding a rough or crumpled veneer ply under the knife without requiring that the operator press the high parts of the edges of the crumpled ply down with his fingers to insert and adjust it under the knife.

In general, according to the invention, a generally rectangular guard is formed of a transparent sheet of material and is immovably mounted on the clipper normal to the work table and parallel to and forwardly of the movable knife of the clipper, the bottom edge of the guard being spaced from the work table such distance that the operator views the cutting edge of the clipper through the guard, and the edge of the guard forms a guide under which the edge of the ply is inserted, the edge of the guard serving to hold flat crumpled or rough edges of the ply, the guard being of sufficient width to prevent the operator from inserting his fingers between the sharpened cutting edges of the clipper. The bottom edge of the guard is rolled, thus forming an inclined surface for aiding and guiding the ply into place. In addition, an elongated, gaseous discharge light is mounted above the clipper parallel to and slightly forwardly of the knife, so that a shadow line is cast by the edge of a bar used for mounting the guard to fall on or near the line where the knife strikes the ply, thus to aid the operator in locating the clipping edge.

For a detailed description of the invention, reference is made to the accompanying drawing, in which

Figure 1 is a perspective view of a portion of

2

the clipper showing the safety guard mounted thereon; and

Figure 2 is a section on the line 2—2 of Figure 1. In the drawing, only one corner of the clipper is shown. The clipper itself is of usual design, and is provided with a flat, horizontal work table 11 and a rigidly mounted, stationary, elongated shear-block 12 having a sharpened cutting edge 13. The movable knife 14 is secured to a rigid, vertically-movable block 15 guided at its end in a suitable guide slot arranged in the side arm 16 of the clipper. A similar arrangement is provided at the other end of the vertically-movable block (not shown). In operation, the knife moves downwardly so that its cutting edge 17 shearingly passes the cutting edge 13 of the stationary shear-block, thus to shear off the edge of a ply such as shown at 18.

In use, if unprotected, the operator tends to use his hands to hold down the edges of a crumpled ply when inserting and adjusting it under the knife, and sometimes thoughtlessly trips the knife with a finger or fingers in line of the moving knife, thus resulting in undesired amputation.

The present invention avoids this injury by provision of a guard which makes it impossible for the operator to insert his fingers under the knife, and yet it does not interfere with visibility of the knife at the shearing edge of the ply.

The guard 20 is formed of a rectangular sheet of transparent material, preferably a plastic bent into a roll shape at its lower edge, as shown at 21, which is spaced from the work table. Means for mounting the guard on the veneer-clipper is provided by a supporting bracket 22 in the form of an angle bar with one leg 23 extending downwardly toward the table and the other leg 24 extending forwardly. The bar is mounted parallel to the knife and rigidly fixed at one end to the side arm 16 as shown at 25, the other end (not shown) being similarly fixed. The guard 20 is suitably fixedly attached to the downwardly extending arm 23, as by screws, with the roll-shape, free, lower edge spaced from the work table forwardly of the knife such distance that the guard acts as a guide for positioning and holding the crumpled ply of veneer properly in line with the knife, but prevents the operator from inserting his fingers between the cutting edges of the clipper.

An elongated, gaseous discharge light 30 provided with a suitable reflector 31 is mounted in any desired manner so that the shadow line, as shown at 32 in Figure 2, cast by the forward edge 33 of the leg 24 falls along or near the line where

the knife strikes the ply, thus to aid the operator in properly positioning the ply when making the clip.

In use, the operator simply slides the ply under the guard, the roll edge 21 forming an inclined surface for guiding the ply in place, thus holding substantially flat any crumples in the ply. When the ply is in proper position, which may be determined by noting the position of the shadow line on the ply, the knife is operated to clip off the unwanted edge portion of the ply without the necessity or possibility of insertion of fingers under the knife.

Having thus described the invention, what is claimed is:

1. In a veneer clipper having a flat work table, a sharpened stationary cutting edge and a movable knife shearingly passing the cutting edge, a safety guard comprising a generally rectangular sheet of transparent material, and a bar secured to the clipper parallel to the knife and to which the guard is secured with one edge of the guard spaced from the work table forwardly of the knife such distance that the guard acts as a guide for positioning and holding the crumpled ply of veneer properly in line with the knife but prevents the operator from inserting his fingers between the sharpened cutting edge and the knife, said bar having a forwardly extending leg and a light so positioned that a shadow line cast by the forward edge of the leg falls along or near the line where the knife strikes the ply.

2. In a veneer clipper having a flat work table, a sharpened stationary cutting edge and a movable knife shearingly passing the cutting edge, a safety guard comprising a rectangular shaped sheet of transparent material and means immovably mounting the guard on the veneer clipper normal to and with one edge spaced from the work table forwardly of the knife such distance that the guard acts as a guide for positioning and holding a crumpled ply of veneer properly in line with the knife, said guard being of sufficient width to prevent the operator from inserting his fingers between the sharpened cutting edge and the knife and having the edge thereof, which is spaced from the work table, rolled, thus forming an inclined surface for aiding and guiding the ply into place.
